(57) **CLAIM**

The ornamental design for a wine rack, as shown and described.

DESCRIPTION

FIG. 1 is a top, front, right perspective view of a wine rack showing my new design;

FIG. 2 is a bottom, rear left, perspective view of the wine rack thereof;

FIG. 3 is a front elevational view of the wine rack thereof;

FIG. 4 is a rear elevational view of the wine rack thereof;

FIG. 5 is a left side view of the wine rack thereof;

FIG. 6 is a right side view of the wine rack thereof;

FIG. 7 is a top plan view of the wine rack thereof; and,

FIG. 8 is a bottom plan view of the wine rack thereof.

The broken lines illustrate portions of the wine rack and form no part of the claimed design.

1 Claim, 8 Drawing Sheets
